UNITED STATES PATENT OFFICE.

NELSON TINGLEY, OF SCRANTON, PENNSYLVANIA.

BLAST-PRODUCING APPARATUS FOR FORGES.

SPECIFICATION forming part of Letters Patent No. 655,591, dated August 7, 1900.

Application filed November 7, 1899. Serial No. 736,156. (No model.)

To all whom it may concern:

Be it known that I, NELSON TINGLEY, a citizen of the United States, residing at Scranton, in the county of Lackawanna and State of Pennsylvania, have invented new and useful Improvements in Blast-Producing Apparatus for Forges, of which the following is a specification.

My invention relates to a blast-producing apparatus for forges.

The objects of the invention are to provide an improved arrangement of water-motor for actuating a fan, to provide in connection with a casing inclosing the water-motor means for conducting heat from the forge into said casing whereby to prevent the water passing through the pipes to the motor from freezing, and to provide means for actuating the fan by other means than that of the motor and from the shaft on which the fan is journaled.

In addition to the above other objects of the invention relate to certain details of construction and combinations and operations of parts, all of which will more fully hereinafter appear.

What I claim as new will be set forth in the claims at the end of the specification.

I have illustrated my invention in the accompanying drawings, in which—

30 Figure 1 is a view in sectional elevation of the draft-producing apparatus. Fig. 2 is a sectional plan view through the fan-chamber, the cover of the motor-chamber being removed to disclose the parts therein. Fig. 3

35 is a plan view of the water-wheel. Fig. 3^a is a sectional view of one of the buckets of the water-wheel. Fig. 4 is a view in elevation showing my apparatus arranged in operative relation with a forge. Fig. 5 is a detail view

40 of a modification in the manner of conducting the heat from the forge to the casing of the apparatus. Fig. 6 is a detail view of another modification of the same. Fig. 7 is a vertical sectional elevation of the upper portion

45 of the shaft supporting the fan and the motor. Fig. 8 is a section through the shaft on the line 8-8 of Fig. 7, and Figs. 9 and 10 are detail views of the nozzle construction.

Referring now to the drawings, the numeral 50 1 indicates a cylindrical casing inclosing the water-motor and the fan operated thereby. The upper part of this casing is provided with

a circular opening, as shown at 2, through which air is drawn in by the fan-blades 3 and discharged through an opening 4 in the side 55 of the casing. The bottom of this casing is also provided with a similar opening 5 for a like purpose, and cast integral with the bottom of the casings and surrounding this opening is a wall 6 of a height approximately one-half that of the entire casing, thereby providing an annular runway 7 around the bottom of the casing. Extending inwardly from opposite sides of the wall 6 and cast integral therewith are arms 8, which support at their 65 inner ends a bearing 9. Extending through this bearing and journaled therein, preferably by means of ball-bearings, as indicated at 10, is a shaft 11. The lower end of this shaft is supported in a cup-bearing 12, cast 70 integral with the outer end of a curved arm 13, flanged at its opposite end, as shown at 14, whereby it may be secured to the bottom of casing 1 by means of suitable bolts passing through said flanged portion. A ball-bearing or an ordinary washer may be provided in the cup-bearing 12, as indicated at 15. On the lower portion of this shaft a belt-wheel or 75 an ordinary gear-wheel may be secured, as shown at 16. On the upper side of casing 1 an arm 17 is shown similar to the arm 13, said 80 arm in this instance being cast integral with the casing. In the outer end of arm 17 is journaled the upper end of shaft 11. A belt or gear wheel 18 is also secured on the upper 85 end of shaft 11.

The numeral 19 indicates a sleeve mounted on shaft 11, between which and said shaft I provide ball-bearings 20. The upper end of bearing 8 is recessed to receive a washer 21, 90 between which and the bottom of sleeve 19 I provide ball-bearings 22.

The numeral 23 indicates the hub of the fan, which hub is secured on the sleeve 19 to revolve therewith by means of a set-screw 24. 95 Extending outward from said hub are arms 25, to which the blades 3 are secured.

The numeral 26 indicates the hub of the water wheel or motor, which is mounted on the lower end of sleeve 19 and secured thereon 100 to turn therewith by means of a set-screw 27. Extending outward from this hub are arms 28, which support at their outer ends an annular rim or flange 29, which projects down-

ward in the runway 7 below the upper edge of the wall 6. Projecting outward from the annular flange or rim 29 are a series of arms 30, on the outer end of each of which arms 5 is provided a bucket 31. As shown in Fig. 3^a, these buckets are conical in shape and are provided about midway of their length with an outwardly-curved bottom 32, the purpose of which construction will presently appear.

10 Extending upwardly through the bottom of casing 1 is a series of pipes 33, each having on its end within the casing 1 a nozzle 34. Each of these nozzles is in the form of a goose-neck—that is, from its base or point of connection with the pipe 33 it is curved upwardly and outwardly toward the wall of casing 1 and then inward for a short distance toward the center of the casing, this outer curved end being provided with a suitable mouth-

15 piece 35 for forming a jet of water, which mouthpiece lies in the same horizontal plane as the buckets 31, so that the water discharged therefrom will strike on the interior of each bucket in succession. As many of 20 these nozzles 34 may be provided as found practicable. I have indicated three such in the drawings. The purpose had in view of curving the nozzles 34 in the manner just described is to provide for the use of a water-

25 wheel of the maximum size. In case a smaller size of wheel is desired for any reason I provide a short pipe-section 36 for each nozzle. In using this the mouthpiece 35 is removed from the nozzle and secured in one end of the 30 pipe-section, the opposite end of the latter being then secured in the discharge end of the nozzle. The curve of the bottoms of the buckets 31 is such that as these buckets pass into the line of the jet of water issuing from 35 a nozzle 34 the jet of water will strike these bottoms at a right angle and not in a slanting direction, so that all the force possible is obtained from the impact of the water on these bottoms. In the further movement of 40 the bucket the jet of water will next strike against the side thereof and further add to its momentum. The water passing through the pipes 33 is supposed to come from a source of supply located at such an altitude 45 as that it will cause the water to issue from the nozzles 34 with considerable force. The jets of water thus issuing from these nozzles and striking the buckets 31 in succession will cause the rim 29 to be rotated very rap-

50 idly, which in turn, through the connections described, will cause a similar rotation of sleeve 19, and thereby cause the fan-blades 3 to be rotated. As the fan revolves it draws in air through the openings 2 and 5 and dis-

55 charges it through the opening 4, from which a blast-pipe 37 leads to the forge 38, as clearly shown in Fig. 4. The hub 26, arms 28, rim 29, arms 30, projecting therefrom, and buckets 31 comprise the water wheel or motor.

60 65 The numeral 39 indicates a waste-pipe leading from the runway 7. In order to direct the water into this pipe, I provide on the

bottom of the runway a ridge 40, extending from one edge of the wall 6 on an incline to the edge of the opening leading to the pipe 70 39. As the water courses around the runway it will come in contact with this ledge and be directed into the escape-pipe 39.

In order to prevent the water splashing over the rim 29, I provide a plate 41, which 75 is in the form of an annulus and is adapted to extend around the upper side of the runway 7. This annular plate is supported on a ledge or offset 42, formed in the outer wall of the casing 1, and around its inner edge is 80 provided with two depending flanges 43 44, which are adapted to project about the upper edge of the rim 29. In addition to this plate I may also provide a sheet-metal cover 45, which is adapted to be secured within the 85 upper portion of the runway 7 and will operate as a further means of preventing the water from escaping over the rim 29 to the bearings.

In order to prevent the water delivered to 90 the motor from freezing, I inclose the lower portion of the casing 1 below the fan and the portion of the pipes 33 and 39 above the ground in a sheet-metal casing 46. Communicating with the interior of this casing is a 95 pipe 47, which is adapted to convey the heat from the forge to the interior of the casing 46, and thus maintain a degree of heat therein that will prevent the water from freezing. I have illustrated in Fig. 4 one arrangement 100 of this pipe. In this construction the forge is supposed to be provided with a chimney 48, and extending at right angles to this chimney is a flue 49, communicating with the pipe 47. It will be seen that the smoke from the 105 forge can pass directly up the chimney 48, while a sufficient amount of the heat will pass through the flue 49 and pipe 47 into the casing 46. In case the forge is not provided with a chimney I can employ either of the 110 constructions shown, respectively, in Figs. 5 and 6. In the first-named figure the flue 49 is shown to be provided with an enlarged opening the mouth of which is vertically disposed and located above the forge, thus allowing the smoke from the forge to pass upward and a certain amount of the heat to 115 pass into the flue 49, as previously described, or in place of this construction the flue 49 may be given a downward extension 50 and 120 provided with an inclined opening 51, the lower edge of which extends downward into the fire of the forge at one side thereof, so that the smoke and gases will pass up on the outside of the pipe 50, while the heat can pass 125 into the opening 51 and through the flue 49 and pipe 47 to the casing 46. The said casing 46 is provided with a door 52, by means of which a lamp or other heat-producing device may be inserted in the casing, so as to 130 preliminarily heat the same before the apparatus has started in operation. The escape-pipe from the casing 46 is indicated by the numeral 53, and this pipe, if desired, may

extend above the casing 46 and then downwardly into the opening 2, as shown in Fig. 4, so that the warmed air of the casing may be again supplied to the fan.

5 The shaft 11, instead of being rotated by means of the water-wheel, may be rotated through the medium of either the gear 16 or pulley 18, and to this end I provide in the space between the sleeve 19 and the shaft 10 a cam-groove 54, having located therein a ball 55, this arrangement operating in the well-known manner—that is to say, when the fan is propelled by the water-motor the ball 55 will rest in the larger end of the groove 54 and the shaft 11 will not be rotated. When the shaft is propelled, however, from either one of the pulleys 16 or 18, the ball will pass to the smaller end of the cam-groove, and thereby cause the sleeve 19 to be rotated 20 with it.

The construction above described will serve to furnish the blast for the forge in a reliable and economical manner, dispensing with the ordinary bellows and with the extra help or 25 extra labor necessary to work the same. It will be seen that the parts described are simple in construction and that there are no parts to get out of order. At the same time by directing the heat from the forge into the casing 30 of the motor I secure the further advantage that the fan may be operated by water-power in cold weather without the liability of the water freezing. At the same time if it should be found impracticable to employ the 35 water-motor for any reason the fan may be propelled by means of the pulleys 16 or 18 by any suitable power.

Having thus fully described my invention, what I claim as new, and desire to secure by 40 Letters Patent, is—

1. A blast-producing device for forges comprising a casing having an annular runway in its bottom, a shaft mounted in said casing, a sleeve revolvably mounted on said shaft, a fan secured on said sleeve and adapted to revolve in said casing, a water-wheel mounted on said sleeve comprising arms, each of which has at its extremity a bucket, one or more water-pipes projecting up into said runway 45 and having discharge-orifices located in the horizontal plane of said bucket, said casing having air-inlets and a discharge-outlet, and a pipe leading from said discharge-outlet to the forge, substantially as described.

55 2. In a blast-producing device for forges, the combination with a casing having an annular runway provided in its bottom, of a shaft mounted in said casing, a fan revolvably mounted on said shaft within the casing, a water-motor revolvably mounted on said shaft and comprising a number of radial arms projecting into said runway, each of said arms having at its outer end a bucket, one or more water-supply pipes projecting up into said 60 casing, each of said pipes having a discharge-orifice located in the horizontal plane of said buckets, an escape-pipe leading from the bot-

tom of said runway, a ledge leading from the inner wall of the runway to the mouth of said escape-pipe, said casing having air-inlets and 70 a discharge-opening, and a pipe leading from said discharge-opening to the forge, substantially as described.

3. In a blast-producing device for forges, the combination with a casing, of a shaft 75 mounted therein, a fan and a water-wheel revolvably mounted on said shaft, pipes leading into said casing for supplying water to operate the water-wheel, said casing having air-inlets and a discharge-opening, a pipe leading 80 from said discharge-opening to the forge, a pipe leading from the bottom of the casing for the discharge of water therefrom, a casing inclosing the said water-motor and the portion of the water supply and escape pipes above 85 the ground, and a pipe leading into said casing and having an open end located in proximity to the forge, whereby the heat from the forge can enter said pipe and pass into said casing, substantially as described. 90

4. In a blast-producing device for forges, the combination with a casing, of a shaft mounted therein, a sleeve mounted on said shaft, a blast-fan and a water-wheel mounted on said sleeve, one or more pipes entering 95 said casing for supplying water to operate said water-wheel, the driving-wheel mounted fast on said shaft, and means for driving the same, clutch mechanism located between the shaft and said sleeve, whereby the fan may 100 be operated either from the water-motor or said driving-wheel, said casing having air-inlets and a discharge-opening, and a pipe leading from said discharge-opening to the forge, substantially as described. 105

5. In a blast-producing device for forges, the combination with a casing having central openings in its top and bottom to afford air-inlets, of an annular wall surrounding the bottom opening to provide an annular runway in the bottom of said casing, a shaft mounted in said casing, a fan revolvably mounted on said shaft, a water-wheel revolvably mounted on said shaft, said water-wheel having an annular flange projecting downward 110 around the upper edge of said wall, and having a series of arms projecting from said flange, each of said arms carrying at its outer end a bucket, an annular plate supported on said casing and covering the said runway, 115 water-inlet pipes for operating the water-wheel, a water-discharge pipe leading from the bottom of said runway, said casing having a discharge-opening for the air, and a pipe leading from said discharge-opening to the 120 forge, substantially as described.

6. In a blast-producing device for forges, the combination with a casing having a shaft mounted therein, of a fan revolvably mounted on said shaft, a water-wheel revolvably mounted on said shaft, said water-wheel comprising a series of arms, each of which carries at its outer end a bucket, and each of said buckets having the shape of a cone and being provided

with a curved bottom, for the purpose described, means for discharging a jet or jets of water into each of said buckets in turn, said casing having a discharge-opening, and 5 a pipe leading from said discharge-opening to the forge, substantially as described.

7. In a blast-producing device for forges, in combination with a casing, a shaft mounted therein, a blast-fan revolubly mounted on 10 said shaft, a water-wheel revolubly mounted on said shaft and comprising a series of arms, each of which carries at its outer end a bucket, one or more pipes projecting into the bottom of said casing, a nozzle secured on the upper 15 end of each of said pipes and being curved outward toward the wall of the casing and having its discharge end curved inward toward said buckets, whereby to discharge a jet of water into each of said buckets in succession, said casing having a discharge-opening 20

for the air from the fan, and a pipe leading from said opening to the forge, substantially as described.

8. In a blast-producing device for forges, in combination with a casing inclosing a blast-fan and a water-motor for operating the same, of a pipe leading from said casing to the forge to conduct the blast of air to the latter, a chimney for conducting the smoke and gases from said forge, a flue leading outward from 25 said chimney at right angles thereto, and a pipe connecting said flue with the interior of said casing, substantially as described.

In testimony whereof I have hereunto set my hand in presence of two subscribing witnesses.

NELSON TINGLEY.
